UNITED STATES PATENT OFFICE

KURT WIEGAND, OF BERLIN, GERMANY, ASSIGNOR TO GENERAL ELECTRIC COMPANY,
A CORPORATION OF NEW YORK

BEACON LIGHT

Application filed February 29, 1928, Serial No. 258,078, and in Germany April 25, 1927.

The present invention relates to aviation beacons and is useful in the arts generally.

For the illumination of flying fields and for the production of beacons for flying courses there have latterly been used in an increasing measure electric gaseous discharge light tubes, as these send out a peculiar far visible light.

The object of the present invention is to 10 secure an increase of the light intensity in the horizontal direction from such light tubes and this is found to be most advantageous as the flyer, if he is at a greater distance from the beacon, observes the light always at an angle 15 of a few degrees relative to the horizontal. In accordance with the invention, therefore, every light tube used for the radiation of light or to give signals is in a novel manner arranged over the peak of a reflector built 20 in the shape of a saddle roof. By the latter the largest part of the otherwise uselessly downwardly directed light rays are spread out in opposite directions and thus the light radiation to all sides of the freely placed 25 light tube is essentially increased in the horizontal.

In order to obtain the best possible light ray distribution in the horizontal plane, the newly developed and arranged reflector is advantageously formed of two roof-like parabolic reflector parts put together with a common focus and the light tube standing over the reflector is arranged in this common focus.

Several examples of forms of construction are shown in the drawing of beacons developed according to the invention.

Figures 1 and 2 show diagrammatically in cross-section and in top view a beacon consisting of an electric light tube and a reflector.

Figure 3 shows a cross-section through a beacon with a somewhat differently shaped roof.

Figures 4 and 5 show in elevation and in ground plan a beacon with two light tubes complementing each other in a square.

Figures 6 and 7 show in elevation and in ground plan a beacon in which a circularly bent light tube is used.

Figures 8 and 9 show in elevation and in

ground plan a beacon with a screw-like wound light tube and a screw-like wound reflector.

The beacon shown in Figures 1 and 2 consists essentially of a reflector *b* built on an even support and has the form of a long drawn out flat saddle roof, as also of a straight light tube *a* arranged freely over the peak of the reflector and having at its ends, electrodes in the usual manner. The light tube *a* may have the usual filler gases or rare gases, and be, as is most usual, operated at high voltage. The light rays issuing downwardly from the freely arranged light tube are, as indicated, spread out to both sides in an approximately horizontal direction by the saddle roof reflector, so that the light radiation of the light tube takes place mainly in the horizontal.

In the light tube of Figure 3 the reflector surfaces of the roof-shaped reflector *b* form parts of two parabolic reflectors as indicated by the dotted lines and which are so pushed into each other, that a common focus results. The light tube *a* is arranged in the latter. In this form of construction the light rays of the light tube *a* going downwardly are all turned off exactly in a horizontal direction, which has as a result an intense light radiation in the horizontal.

In order to obtain as uniform as possible a light distribution in the entire horizontal plane it is possible, as shown in Figures 4 and 5, to use as reflectors two angle pieces *b*, *b'* with a roof-shaped cross-section. Both angle pieces are as especially shown in Figure 4 arranged at a different height and, moreover, so that they complement each other as a square when looking down on them. Over each angle piece *b*, *b'* there is each time arranged a light tube *a*, *a'* of the same angle form, which at the ends have the electrodes, *c*, *c'*. These light tubes also lie in a different height and complement each other to a square. The angle shape of the reflectors and light tubes favors a uniform light radiation in all four main directions of the horizontal plane, and due to the different position in height of the angle pieces and of the light tubes, the interiorly lying parts of the angle pieces and light tubes can radiate the light

in a horizontal direction without hindrance. There cannot therefore occur any noteworthy loss of light.

A beacon light of a square form can naturally be obtained also by the combination of 5 four straight roof reflectors and four light tubes. The roof reflectors and light tubes may also be combined to a polygonal, a three-cornered or other desired closed figure, which 10 guarantees a good light distribution to all sides.

In the form of execution as in Figures 6 15 and 7 there are used two roof reflectors *b*, *b'* each of a semi-cylindrical shape, which are likewise arranged at different heights in 20 order to avoid obstructing any part of the horizontal radiations. Over these roof reflectors there extends in this case a single light tube of a circular shape and provided with the step-like bend *d*.

Figures 8 and 9 finally show a beacon light 25 in which as well as the roof-shaped reflector *b* the light tube *a* lying above it are wound each like an upwardly rising screw thread.

26 What I claim as new and desire to secure by Letters Patent of the United States, is:—

1. A beacon light comprising, in combination, a tubular source of light having a distinctive configuration, and two reflecting surfaces 30 whose line of junction is adjacent to and conforms to the configuration of said light source, said surfaces reflecting rays from the adjacent portion of said source in opposite directions horizontally, each point on said 35 tubular light source being in such a plane as to avoid interference with the horizontal radiations emanating from the opposite side of 40 said source.

2. A beacon light comprising, in combination, a tubular source of light having a distinctive configuration, and at least one reflector having two reflecting surfaces whose line of junction is adjacent to and conforms to the configuration of said light tube or tubes, 45 opposite sections of said light source being so arranged as to avoid interference with the horizontal light rays emanating from the opposite side of said source.

3. A beacon light comprising, in combination, a tubular source of light having a distinctive configuration, and a reflector having two parabolic surfaces so shaped and mounted with respect to said light source that the adjacent part of said tubular light source is 55 continuously at the common focus of said parabolic surfaces, said surfaces reflecting rays from the adjacent portion of said source in opposite directions horizontally, each point on said light source being in such a plane as to avoid interference with the horizontal light rays emanating from the opposite side of said source.

4. A beacon light comprising, in combination, a curved tubular source of light, the projection of said light source on a horizontal

plane forming substantially a closed figure, and two reflecting surfaces whose line of junction is adjacent to and conforms to the curvature of said light source, said reflecting surfaces each redirecting rays from the adjacent portion of said light source into a substantially horizontal direction, each point on said tubular light source being in such a plane as to avoid interference with the horizontal radiations emanating from an opposite sector 75 of said light source.

In witness whereof, I have hereunto set my hand this 15th day of February, 1928.

KURT WIEGAND.
